UNITED STATES PATENT OFFICE.

THOMAS A. MCKEE, OF BELOIT, KANSAS.

PERPETUAL CALENDAR.

SPECIFICATION forming part of Letters Patent No. 398,172, dated February 19, 1889.

Application filed May 29, 1888. Serial No. 275,507. (No model.)

To all whom it may concern:

Be it known that I, THOMAS A. MCKEE, a citizen of the United States, residing at Beloit, in the county of Mitchell and State of Kansas, have invented new and useful Improvements in Perpetual Calendars, of which the following is a specification.

My invention relates to improvements in perpetual calendars, having for its object to provide (in combination with a calendar) a table to show the relation of night to day in the various parts of the year; and it consists in a certain novel construction and arrangement of devices, fully set forth hereinafter in connection with the accompanying drawings, wherein—

Figure 1 is a face or front view of the improved calendar. Fig. 2 is a rear view of the same. Fig. 3 is a vertical central sectional view thereof. Fig. 4 is a view of the year-disk detached.

Referring to the drawings, A designates the body of the calendar, which may be of any preferred form or ornamental design, in which is formed the opening B; and C represents a circular table of the days of the week, five weeks being represented in the table. Within the said table is mounted, upon a suitable pivot, a disk, D, the periphery of which 25 is divided into thirty-five spaces, to align, respectively, with the thirty-five days represented on the day-table. The thirty-one days of the month are represented by figures in the spaces on the disk D, leaving four vacant 30 spaces which are covered by the segment of a disk, E, which is a section of a disk in the form of a sector, and is mounted on the same pivot as the disk D. When a month has less than thirty-one days, the said segment of a 35 disk is moved to cover the unnecessary figures.

A series of perforations, F, are formed in the edge of the disk D, and a spring-catch, G, is attached to the body and is adapted to engage either of the said perforations to lock the disk in the desired position, it being evident that the disk must be adjusted each 40 month in order to bring the first day of the month on the proper day of the week.

A disk, H, is mounted on the rear side of the body, and its periphery is divided into a series of spaces, h h, (preferably thirteen in number,) in which are the names of the months of the year, (two spaces being allotted to February.) Only one of these spaces is 50 visible at a time through the opening B, and each space is divided into a dark and a light section, the relative sizes of which differ in different parts of the year. The dark section is designed to represent "Night" and the 55 light section "Day," so that their relative sizes indicate the relation between the day and night in the various parts of the year. The year-disk is moved on the last day of each month, to bring a different month opposite 60 the opening in the body; hence the two spaces designated "February," one being for use in leap-year.

The periphery of the year-disk is provided with perforations I I, in which the spring- 70 catch K engages to lock the disk in the desired position.

I claim—

In a perpetual calendar, the combination of the body provided with a circular day-table, 75 C, and an opening, B, the revoluble month-disk concentric with the day-table and containing thirty-one days, the segment of a disk, E, concentric with and arranged on the month-disk, and adapted to cover the extra days in 80 months containing less than thirty-one days, the year-disk mounted on the rear side of the body and provided with spaces containing the names of the months, which spaces are partly darkened to indicate the relation between the 85 night and day in the indicated month, one of said spaces being adapted to be exposed through the opening B at all times, substantially as specified.

In testimony that I claim the foregoing as 90 my own I have hereto affixed my signature in presence of two witnesses.

THOMAS A. MCKEE.
